UNITED STATES PATENT OFFICE

HORACE LEHR, OF EASTON, PENNSYLVANIA

DESIGN FOR A COMBINED DESK AND RADIOCABINET

Application filed August 23, 1930. Serial No. 36,747. Term of patent 3½ years.

To all whom it may concern:

Be it known that I, HORACE LEHR, citizen of the United States, residing at Easton, in the county of Northampton and State of Pennsylvania, have invented a new, original, and ornamental Design for Combined Desk and Radio Cabinet, as shown in the accompanying drawing and described in the following specification.

In the accompanying drawing the illustra-

tion represents a perspective view of a combined desk and radio cabinet embodying my invention, showing my new design with the sliding doors for the radio compartment closed.

I claim:

The ornamental design for a combined desk and radio cabinet as shown and described.

HORACE LEHR.
